HOOD LATCH

Arthur Claud-Mantle, Trumbull, Conn., assignor to Bassick Company, Bridgeport, Conn., a corporation of Connecticut

Application December 4, 1953, Serial No. 396,215

18 Claims. (Cl. 292—54)

This invention relates to hood latches for automobiles and more particularly to alligator-type hood latches where the parts of the latch are carried by the forward end portion of the lid and a lower fixed part adjacent a grille at the forward end of the engine enclosure.

An object of the present invention is to provide an improved latch of this general type.

Another object is to provide an alligator hood latch in which, when the lid is moved from the open to the closed position, the lid is guided in an improved manner without damage to the lid or adjacent parts of the car, the structure of the latch being such that serious defects of latches now in use are overcome.

Another object of the invention is to provide a latch of the alligator-type with improved safety catch means for the hood lid.

Another purpose of the invention is to furnish a superior latch mechanism adapted for manual operation from the grille portion of the hood.

In the accompanying drawings:

Fig. 1 is a partial front end elevation of an automobile equipped with a hood latch embodying the invention;

Fig. 2 is a fragmentary top plan view, with parts broken away, of the hood and its latch mechanism, the lid being in its latched position;

Fig. 3 is an elevation of the latch mechanism locking from the front end of the car, certain parts of the hood being indicated by broken lines;

Fig. 4 is a side elevation of the latch with certain parts of the hood shown by broken lines;

Fig. 5 is a section on line 5—5 of Fig. 3, the upper and lower carrying plates for the latch mechanism being shown in this case by full lines;

Fig. 6 is a section on line 6—6 of Fig. 4;

Fig. 7 is a fragmentary top plan view of the lower plate member of the latch, the primary latching lever and the safety catch lever being in their protracted positions with respect to the latch aperture;

Fig. 8 is a bottom plan view of the latch plate member shown in Fig. 7;

Fig. 9 is a partial view of the lower plate member showing both the primary latching lever and the safety catch lever in their released positions;

Fig. 10 is a view similar to Fig. 1 showing a modified form of latch in which the keeper, instead of being carried by the lid, is carried by the lower fixed part of the engine enclosure;

Fig. 11 is a fragmentary plan view with parts broken away of the latch mechanism shown in Fig. 10;

Fig. 12 is an enlarged front elevation of this form of latch mechanism;

Fig. 13 is a side elevation of this latch mechanism;

Fig. 14 is a section on line 14—14 of Fig. 12;

Fig. 15 is a section on line 15—15 of Fig. 13;

Fig. 16 is a top plan view of the upper plate member of this latch, with the safety catch lever and the primary latching lever in their normal positions; and

2

Fig. 17 is a detail perspective view of the safety catch lever looking toward the inner side thereof.

In the form illustrated, by way of example, in Figs. 1 to 9, inclusive, the organization of parts includes a depending rigid keeper in the form of a plunger or post carried by the forward end of the lid and in this instance having a conical head at the lower extremity adapted to be latched by a latching member mounted on the lower fixed part of the engine enclosure. As a part of the latch mechanism, there is provided a lifting spring for the lid, but this spring, instead of embracing the keeper as in some prior latches, is spaced in a forward direction with reference to the keeper and is mounted upon the lower member of the latch, as hereinafter more particularly described. The keeper is adjustably connected at its upper end portion with a mounting that comprises upper and lower attaching plates between which is interposed a plate-like keeper-carrying member which is provided within the hood lid. The lower member of the latch comprises a main latch plate that is provided with a throat or aperture for receiving the keeper head and is further provided with a primary latching lever pivoted to the plate at the under surface thereof and having a lug or tab engageable over and releasable from the upper part of the conical head on the keeper. The latch plate just referred to is arranged below a carrying plate on the lower fixed part of the engine enclosure and a portion of this carrying plate is sandwiched between the latch plate and a keeper-guiding member extending in an upward direction from the main latch plate. In this instance, the keeper-guiding member is in the form of a vertical channel having lower flanges or foot portions by means of which this member is secured to the main latch plate with the carrying member or mounting member interposed. The guiding channel member has associated with it at one side, as hereinafter described, a safety catch member which is in the form of a lever mounted to swing in a horizontal direction and having a lug adapted to overlie the keeper head for the purpose of holding the hood lid in the safety position. The channeled guiding member in this form is also provided above and somewhat forwardly of the latch aperture with a casting portion in which is mounted a lid-lifting spring, as hereinafter described, said spring acting upon a stem or plunger projecting upwardly from the guiding member and adapted to be depressed by engagement with the upper mounting structure of the keeper for the purpose of energizing the spring when the lid is closed. The latching lever is operable manually from the forward end of the hood and for this purpose the body of the lever is extended from the latch mechanism in a direction which is transverse to the hood and is provided with an extension that has a forwardly offset manipulating portion that is easily accessible through the grille in a location where it is to one side of the longitudinal median line of the hood.

In the drawings, the rearwardly hinged hood lid is indicated at 20, the grille at the lower forward end of the hood at 21, the latch device in general at 22, the carrying plate within the upper part of the lid at 23, the carrying plate fixed to the lower stationary part of the hood enclosure at 24, the rigid depending keeper at 25, the mounting for the upper end of the keeper at 26, the apertured main latch plate at 27, the latch aperture or throat at 28, the channeled keeper-guiding member at 29, the primary latch lever at 30, the latching lug of lever 30 at 31, the forwardly disposed manipulating portion of the latching lever at 32, the safety catch member or lever at 33, the spring-enclosing portion of the guide member 29 at 34, the lid-lifting spring enclosed within this portion at 35, and the stem or plunger for compressing the spring at 36.

Taking up first the structure of the latch plate 27 of

the lower or fixed latch member, this plate is, in general, similar to a latch plate disclosed in my application, Serial No. 384,120, filed October 24, 1953, now Patent No. 2,781,214, dated February 12, 1957, the same being adapted to cooperate with a conical head 37 integral with the keeper 25 at the lower end of the latter, the keeper-receiving aperture being elongated longitudinally of the hood so as to permit some relative forward and rearward movement of the lid and hood body when the lid is in the closed position. The lower plate has in association with the aperture two depending and continuous flanges, each flange extending along one side of the elongated aperture so as to provide a skirt which prevents the keeper head from extending under the plate and becoming jammed therewith. The latching lever is pivoted to the plate adjacent the forward end of the aperture and extends along the left-hand side of the aperture, as viewed in Fig. 2, and the lever lug 31 is normally projected through the flange or skirt structure 38 between the ends of the aperture, said lug being supported so that it can overlie the keeper head in any position of the head along the length of the aperture.

As shown in Fig. 2, a portion 39 of the latch lever 30 extends laterally from the left side of the latch plate with the offset manipulating portion 32 arranged in a forward position where it is easily accessible. The forwardly disposed pivot of the latch lever 30 is indicated at 40, and at 41 is an arm projecting rearwardly from the body of the latch lever, which arm extends into a guiding slot 42 at the rear edge of the plate. The latch lever 30 is acted upon by a coil spring 43, one end of which is hooked into an opening 44 in the latch plate so as to engage the edge of the latch plate, while the opposite end of this spring has hooked engagement with a perforated lug 45 integral with the arm 41 of the latch lever and projecting downwardly therefrom. The edge portion 46 of the latch plate, with which the hook 47 of spring 43 is engaged, is depressed or channeled, as shown in the drawings, so that it, in connection with the aperture 44, enables the spring coil to be straight at this end without distortion, while, at the same time, some rocking of the coil on its axis is permitted. The other end hook provided upon the spring, indicated at 48, passes through a round hole 49 in the lug 45 and the extremity of this hook, which is downwardly disposed, is engaged in a somewhat wider notch 50 in the lower edge of the lug 45. Due to these provisions, the spring 43 will act on the latch lever 30 in an effective manner in all of the different positions assumed by the lever, it being possible for the spring coil to remain straight and effective at all times as a result of the rockable arrangement of the end hooks.

In this form, the manipulating portion 32 of the latch lever is part of a rod-like member that is formed separately from the lever portion 39 and secured thereto by suitable means, as by welding, the portion 39 being provided with an offset aperture part 39a through which the end of the rod portion is extended and then welded in place.

As best shown in Fig. 8, the latch plate 27 has integral depending flanges along two sides, and the latch lever extends through a slot 51 in one of these flanges. The keeper-guiding member 29 is provided with lower flanges or portions 52 and 53 constituting a plate formed integrally with the guiding member, the flange 52 at one side being of greater length than the flange 53 of the other side, and fastening screws 54 having hexagonal heads above the flange 52 pass through holes in this flange and holes in the carrying plate 24 and have threaded portions engaging threaded sockets 55 formed integrally with the latch plate 27 and extending downwardly from this plate. Similarly a screw 56 passes downwardly through the flange 53 and the carrying plate into a threaded socket 57 on the latch plate, the arrangement being such that the keeper-guiding member is firm-

ly secured in position above the latch plate with its channel portion in line with the latch aperture, as best shown in Figs. 7 and 8.

The keeper-guiding member 29 made of sheet metal has side walls or cheeks 58 that are parallel to each other and lined up with the skirted side portions of the latch aperture and these walls at their lower portions, that is to say, in the portions below the spring-enclosing portion indicated at 59, extend from the region of the rear edge of the latch plate to a location close to the forward end of the latch aperture. The keeper-guiding member shown is made from a metal blank bent to form the spring-enclosing portion which, in plan, has the shape shown in Fig. 7 and has lug or tab portions meeting each other and providing top and bottom walls between which the lid-lifting spring 35 is confined, these top and bottom walls being cut away to provide the guide openings in which the stem or plunger 36 is mounted. This spring-enclosing portion, associated with the keeper-guiding member, overhangs the portion of the main latch plate forwardly of the latch aperture, as shown in the drawings, and the arrangement is such that the upper end of the stem 36 can make contact with the mounting of the keeper, as hereinafter described.

The spring 35, as will be noted from Fig. 5, has its lower end abutted against the bottom wall of the spring casing and the upper end of the spring abuts a collar 60 integral with the stem somewhat below its upper end; and normally the spring 35, which is under compression, will hold the stem in an elevated position with the collar 60 against the top wall of the spring casing, in which position a substantial portion of the stem will extend upwardly from the casing.

The latch member or lever 33 is a member pivoted adjacent the rear edge of the assembly and swingable in a horizontal plane and having adjacent its forward end a projecting part movable through a slot in the adjacent side wall of the keeper-guiding member, said projection being normally in a position in which it overlies the conical head of the keeper. The rear end of the lever is pivoted to the rear edge portion of the corresponding keeper-guiding wall, for which purpose said wall is provided with integral upper and lower parts formed to present knuckles that hold the upper and lower ends of a fixed pivot pin 61 on which the lever 33 is pivotally mounted. As shown in Fig. 6, the lever 33, in this form, is an elongated sheet metal member of channeled cross-section with the channel facing toward the outer surface of the adjacent keeper-guiding wall. The lower wall of lever 33 is provided adjacent the forward end with an integral extension providing a lug 62 which is the safety catch projecting part mentioned above. The lug operates in a slot or clearance opening 63 in the keeper-guiding wall. The pin 61, mentioned above, is embraced by a helical spring 64 arranged in the channel of lever 33 and having a projecting end bearing against a part of the lever and another projecting end bearing against the adjacent portion of the side wall; and this spring holds the lever 33 against the keeper-guiding wall with the lug 62 extending into the channel of the keeper-guiding member, as shown in Figs. 6 and 7.

For the purpose of providing a camming connection between the lever 33 and the primary latching lever, the lever 33, in this form, carries adjacent the rear end a depending finger or pin 65. In this form, the pin 65 has a head 66 and is inserted through holes in the upper and lower walls of lever 33 and has a lower end extended through a clearance opening 67 in the latch plate so that the pin has a portion lying in the plane of the lever 30 and engageable with a side edge of the lever body. As shown in Fig. 8, the pin 65 is at some distance from the latch lever body when the latter is in the latching position, but the lever body has an edge portion 68 adapted to engage the pin 65 for the purpose of swing-

ing the catch lever to the position shown in Fig. 9, which is its keeper-releasing position.

It may be noted here that when the latch lever is in the latched position, the edge portion 68 is at such a distance from pin 65 that the pin is not engaged by the lever until the lug of the latch lever has cleared the latch aperture. Approximately at the time that the latch clears the latch aperture, the latch lever engages the pin 65 and the releasing movement of the catch lever 33 commences. In other words, the latch lever has a continuous releasing movement during the first part of which the latching lug is moved to full release and during the remaining part of which the catch lug 62 is moved so that the keeper is fully cleared by the catch lever.

Taking up next the mounting 26 for the keeper 25, this mounting comprises lower and upper mounting plates 69 and 70 between which a portion of the upper carrying plate 23 is interposed. The lower plate 69 is a rectangular plate having a downwardly dished rectangular portion 71 at the center in which a threaded socket 71^a for the keeper is provided, a part of this socket being formed in the material of the plate 69 and another part by a nut 72 which is welded in place in the dished part of the plate. Extended integrally from the dished part of the plate are four strengthening ribs, two of which are relatively wide and flat, as indicated at 73, and are in line with each other and substantially in the longitudinal median line of the hood. The lower flat face of one of these ribs 73 is arranged to overlie the upper end of the stem 36, as shown in Fig. 5. Near the corners of the plate 69 are slots 74 elongated in a direction lengthwise of the hood for purposes of longitudinal adjustment of the keeper, and screws 75 provided with lower hexagonal heads extend upwardly through these slots and through holes in the carrying plate 23 and into threaded sockets 75^a provided on the upper plate 70, the arrangement being such that when the keeper is accurately positioned in a longitudinal direction, it can be firmly secured to the carrying plate.

The upper end of the keeper 25 is projectable upwardly through the upper plate 70 to a certain extent, as shown, for example, in Fig. 3, this being permitted because of the provision in plate 70 of a clearance aperture 76, and the carrying plate has a corresponding aperture.

The keeper 25 is a post-like or bolt-like member of which the conical head 37 is an integral part presenting an upper flat latching face over which the primary latching lug 31 engages (Fig. 6), the stem portion immediately above the head being cylindrical and smooth, as indicated at 77. Above this portion 77 is a portion 78 which is of slightly larger diameter and provided with a suitably roughened surface, as by knurling. In this form, the vertical dimension of the knurled part 78 is about the same as that of the smooth portion 77. Above the portion 78, substantially the entire remaining portion of the stem is externally threaded, as shown at 79, the outside diameter of the threaded portion being somewhat greater than that of the knurled portion. The threaded portion is adapted to engage the threads of the upper socket 71^a, previously mentioned. A nut 80 which may be a hexagonal nut is placed on the threaded portion 79 below the mounting and by screwing up the nut 80 against the lower face of the keeper mounting, the keeper can be securely held in any selected vertical adjustment.

It will have been noted that in the present latch the lid-lifting spring which raises the lid by exerting force against the mounting of the keeper member in a location forwardly of the keeper, does not embrace the keeper, as in some prior constructions, and, hence, with a keeper constructed and arranged as above described, it is possible to effect adjustment of the keeper much more readily than has been possible heretofore. Heretofore, owing to the provision of a spring helix and a cup member about the keeper, providing a definite obstacle, it has been a difficult matter to adjust the keeper even by the use of a

screwdriver inserted into a nick in the conical head. With the present construction, the knurling of the keeper shank or stem enables the keeper to be turned by hand located in the vertical direction. Also, the keeper can be released from its secured position very readily by hand manipulation in case further adjustment is desirable. It is unnecessary to use a screwdriver for adjustment of the keeper.

It will be understood that in the operation of the improved latch, the latch can be readily released from the latched position, shown in Figs. 1 to 6 in full lines, by inserting the hand through the grille opening and pulling the manipulating part 32 of the latch lever in a forward direction. This will withdraw the lug 31 from the latch aperture, as previously described. The lid-lifting spring will then lift the lid as a result of the stem 36 pushing the lid in an upward direction. If the primary latching lever is not swung sufficiently to swing the safety catch lug 62 out of the channel of the keeper-guiding member, the upper face of the conical head of the keeper will abut against the lower face of the lug 62, as indicated by the broken lines in Fig. 6, and, therefore, the catch lever 33 will serve to hold the lid in the safety position in which, as customary, the lid is opened to a relatively slight extent. If, however, it is desired to obtain a full opening of the lid, the primary lever is actuated to the full extent so that, as previously described, the catch lever is moved out of the way, the safety catch lever being actuated in the manner previously described. In this way, the lid can be moved up to the customary fully raised position by hand manipulation of the lid after the primary latching lever has been fully actuated, and it is understood, of course, that upon such full actuation of the latching lever to the releasing position, the lid-lifting spring will raise the keeper to a point where it is substantially above the level of the catch lever lug.

The safety catch lever serves as a safety catch member to prevent full release of the keeper in case the lid when closed down is not fully secured or, due to some cause, escapes from the hold of the latching lever and, in such case, the catch lever securely retains the keeper head in a position such as shown by the broken lines in Fig. 6, the keeper head being at this time rather closely confined between the opposite walls of the guide channel or like keeper-guiding member. Under such circumstances, the keeper head is effectively prevented from lifting out of the lower part of the keeper guide that is over the latch aperture.

When the lid is closed, the keeper-guiding member 29 serves a very important function. The upper end of this member receives and guides the cone-shaped keeper head at a distance well above the lower latch plate and guides the keeper to the latch plate. The guiding effect is particularly one which guides the lid in a lateral or transverse relation to the engine enclosure so that the lid, in being closed, is not out of line with the longitudinal median line of the hood. By this guidance, the closing and latching of the hood is greatly facilitated and damage adjacent the side edges of the lid (either to the lid itself or to the fenders) is prevented. Moreover, it is possible to obtain this centering action in a structure having a simple and relatively short keeper member.

In closing the lid, the keeper head, when it reaches the catch lever lug, forces the catch lever out of the way against the action of its spring and the head then passes downwardly to engage the latching lug 31 and to be latched thereby. The catch lug, after the head passes, moves back to the safety position.

It will be apparent that this structure has a guiding member for the keeper including in its structure a lid-lifting spring which urges the keeper head toward a safety position between a lower primary latch lever and an upper catch lever.

As in this structure the carrying plates for the keeper and lower latch member respectively are sandwiched

between upper and lower mounting members or parts in each instance, the rigidity and strength of the latch mechanism is greatly increased.

In the modified structure shown in Figs. 10 to 17, inclusive, the chief difference over the form first described arises from the fact that here the arrangement of the keeper and the apertured latch plate is reversed, the keeper being an upwardly directed member fixed in position on the lower part of the engine enclosure and the apertured latch plate being mounted on the lid. In this particular case also, no lid-lifting spring is employed, although if desired such a spring may be incorporated in the structure. Structurally, a great many of the parts of the latch are similar to those previously described.

In this form, as well as in the form first described, the forward edge of the hood lid is shown as lying in immediate proximity to the grille when the lid is closed, with no separating member, but if desired a separate cross member or bridge piece may be used as a support for the forward edge of the lid.

In this form of Figs. 10 to 17, inclusive, the manipulating member for the latch lever indicated at 81 extends toward the right of the hood (Fig. 10) rather than the left, and is accessible by way of a slot or opening 82 associated with the upper part of the grille 83. The upper latch member comprising the latch plate 84 and the keeper-guiding member 85 is applied to the carrying plate 86 associated with the lid, in the manner shown in Fig. 12, with the keeper-guiding member in a depending position, the carrying plate being sandwiched in between the two members, as described above. The keeper 87 extends upwardly from the lower carrying plate 88 and the latch is engaged by having the latch member, carried by the lid, move downwardly over the fixed keeper. The latch plate 84 and its associated parts are in this instance substantially identical to those previously described. The latch lever being disposed above the upper carrying plate, as shown in Fig. 12, makes it necessary for this carrying plate to have an aperture 89 through which a part 90 of the manipulating handle portion 81 is extended, whereby the handle or gripping part of the lever is disposed below the upper carrying plate in a location where it is readily accessible in the recess 82. In this case, the pin 91, which corresponds to the pin 65 previously described, has a head 91a at the lower end of the pin and the pin is fixed in position in a suitable manner relatively to the catch lever.

The keeper-guiding member 85 is generally similar to the member 29 previously described, but as no lid-lifting element is associated with this member, the channelled keeper guide, at its closed forward end, has a transverse wall 92 at right angles to the side walls, this transverse wall having its inner face substantially in line with the forward end of the latch aperture. These are the principal, if not the only distinctions of this latch member, over the one previously described.

The keeper member 87 is provided with an upper conical head 93 of the kind previously described and it cooperates with the guiding member, the safety catch lever and the primary latching lever in the manner previously described taking into consideration that the keeper is the fixed member rather than the movable member of the assembly. In view of the preceding description, it is thought that the mode of operation of this form of latch will not require detailed description.

In the closed position of the latch shown in Fig. 12, the latching cone 93 is engaged by the latching lever and the catch lever positioned below the latching lever serves as a safety to prevent more than a slight upward movement of the lid. The keeper member is shorter than in the form first described because it is possible to bring the carrying plates closer together where the spring-pressed lid-lifting stem is omitted. In this form, the knurled portion 94 of the keeper is somewhat longer than

in the first form and extends substantially from the head of the keeper to the threaded lower part of the keeper stem.

It will be readily understood that when the lid is raised to a substantial extent, the keeper is readily accessible for manual manipulation for the purpose of raising or lowering the keeper head, if such adjustment is desirable. By this adjustment, the keeper head can be placed in exactly the desired position vertically to cooperate in an optimum manner with the upper member of the latch.

When the lid is lowered for closing the same, the keeper-guiding member acts substantially in the manner previously described to guide the lid and center it so that its median longitudinal line is coincident with the median longitudinal line of the hood structure. The lower mouth portion of the keeper guide engages over the upwardly pointed keeper head and the guide then moves down over the keeper head, the catch lever being engaged and swung out of the way and the latch lever being then engaged and swung out of the way and moving back to underlie the head in the position shown, for example, in Fig. 15.

In the present case, there is no need for a spring to move the lid upwardly when it is released. To release the lid, the manipulating portion of the latch lever is pulled in a forward direction and the lid can be given an initial lift by the hand which grasps the manipulating portion of the latching lever. As soon as the lever has been swung to a certain extent, as in the first form, the safety catch lever begins its releasing movement and hence it is apparent that by giving the lever a full swing and maintaining the grip on the lever, the lid can be moved upwardly beyond the safety catch position. If necessary the other hand of the operator can be used in connection with the lid-lifting operation.

It is apparent from the foregoing that, by the latch structure herein described, the lid of the hood is controlled and guided in an improved manner when and as the lid is being closed so as to interengage the latch parts in a proper and correct manner so as to accomplish effective latching, while, at the same time, eliminating damage to the lid or adjacent parts of the car due to the misalignment of the descending lid which, in many preceding latch structures, has been a serious drawback. The structure of the latch in general is also improved as compared to previous latch structures. The keeper and its mounting structure are also improved permitting much easier adjusting of the keeper longitudinally (vertically) than has been possible heretofore. Hand manipulation of the keeper is all that is necessary for this adjustment and jamming of the keeper in a given adjustment is prevented or inhibited by the described structure. Moreover, a keeper of minimum length can be employed. The safety catch (secondary latch) provisions of the latch are also of an improved kind, likewise the provisions whereby the lid, after being released, is lifted from the initial position. In one aspect of the invention, a considerably improved device for lifting the lid to an extent by spring pressure is provided. In another aspect of the invention, the latch is simplified to such an extent that a lifting spring for the lid is not required, the primary latching lever being under the control of a manipulating portion carried by the lid which manipulating portion of utility in raising the lid after the keeper has been engaged by the latching lever.

While the guiding member for the keeper is shown as being of channel form, the invention is not limited to guide channel. It is noted that, in both forms described above, the guiding member carries a preliminarily acting latch member engaged before the engagement of the primary latching member and serving as a safety catch. In both forms, the safety catch remains in fully operative position during a movement of the primary latch that will release the keeper.

While two forms of the latch are disclosed herein, they are by way of example only and various modifications

and changes in the details may be made without departure from the principles of the invention or the scope of the claims.

What I claim is:

1. In a latch for use on hoods of the alligator type having a fixed hood body and a rearwardly hinged lid one of which parts carries at the forward end a postlike keeper uprightly disposed and having a base and a distal head: latching means for mounting on the other of said parts to cooperate with the keeper comprising a latch plate having a keeper-receiving aperture elongated longitudinally of the hood, a guiding member in fixed relation to said latch plate having substantially parallel walls extending toward the keeper base at opposite sides of said aperture and disposed in planes parallel to the longitudinal axis of the hood and adapted to contact the keeper at opposite sides of the keeper head, a spring-biased primary latch lever movable in a substantially horizontal plane and pivoted to said latch plate at a point forwardly of said elongated aperture and somewhat offset from the longitudinal axis of said aperture, said lever having a portion thereof engageable with the head of the keeper for latching action, said lever having an operating extension for manual manipulation disposed in an opening at the front of the hood body, a spring-biased pivoted safety catch lever associated with one of the walls of said guiding member at the exterior of said member and swingable in a horizontal plane substantially parallel to the operating plane of said primary latch lever and having a lug movable through a slot in said wall to overlie the head of the keeper in the safety position of said catch lever, and an upright projecting element carried by said catch lever exteriorly of said guiding member and adjacent the pivot of said catch lever, said projecting element being engageable by an edge portion of said primary latch lever so that after movement of said primary lever to release the keeper and on continued movement of said primary lever the catch lever will be moved to an inoperative position.

2. In a latch for use on hoods of the alligator type having a fixed hood body and a rearwardly hinged lid one of which parts carries at the forward end a postlike keeper uprightly disposed and having a proximate base and a distal head: a guiding member in fixed relation to the other of said parts having substantially parallel walls extending toward the keeper base and serving to contact the keeper by engagement with the head of the latter at opposite sides, a spring-biased pivoted safety catch lever associated with one of the walls of said guiding member at the exterior of said member and swingable in a substantially horizontal plane and carrying at a distal end a lug movable through a slot in said wall to overlie the keeper head and retain the keeper in the safety position, a spring-biased keeper-head-engaging primary latch lever having a pivot in fixed relation to said other part of the latch which lever is swingable in a plane substantially parallel to the operating plane of said catch lever, and means operable manually from the forward end of the hood for swinging said safety catch lever and said primary latch which lever is swingable in a plane substantially positions.

3. A structure as defined in claim 2, in which the said guiding member is mounted on the hood body and said parallel walls of said guiding member are interconnected at their forward ends by a cross wall, said cross wall enclosing a lid-lifting spring-pressed stem.

4. A structure as defined in claim 2, in which said safety catch lever is of substantially U-shaped cross section having inturned upper and lower flanges, and in which said lug to overlie the keeper head is an extension of one of said flanges.

5. A structure as defined in claim 2, in which said parallel walls of said guiding member are interconnected by a cross wall in a location disposed toward the forward end of the hood, and in which said safety catch lever has

its pivot located adjacent the opposite or free end of the associated wall.

6. A structure as defined in claim 2, in which said guiding member is fixed to the hood body.

5 7. In a latch for use on hoods of the alligator type having a fixed hood body and a rearwardly hinged lid one of which parts carries at the forward end a postlike keeper uprightly disposed and having a base and a distal head: a guiding member for guidance of the lid in closing having fixed relationship to the other of said parts and of substantially U shape in plan, the intermediate or connecting part of the U being disposed toward the front of the hood and the sides of the U being walls extending rearwardly substantially parallel to each other and serving to contact the keeper by engagement with the keeper head at opposite sides, a spring-biased pivoted safety catch lever disposed exteriorly of said guiding member along one of said walls and having its pivot adjacent the rear end of said last-named wall, said safety catch lever being swingable 20 in a substantially horizontal plane and provided with a lug movable through a slot in said wall to overlie the keeper head and retain the keeper in the safety position, a spring-biased primary latch lever having a pivot in fixed relation to said other part of the latch which lever is swingable in a plane substantially parallel to the operating plane of the catch lever, and means operable manually from the forward end of the hood for swinging said safety catch lever and said primary latch lever to their releasing positions.

30 8. In a latch for hoods having a fixed hood body and a rearwardly hinged lid one of which parts carries at the forward end a postlike keeper uprightly disposed and having a distal head: a piloting guide member for guidance of the lid in closing having fixed relationship to the 35 other of said parts substantially U-shaped in plan, the intermediate or connecting part of the U being disposed toward the front of the hood and the sides of the U being walls extending rearwardly substantially parallel to each other and serving to contact the keeper by engagement of the keeper head at opposite sides, one of said walls being equipped intermediate of the height of the wall with a spring-biased latch element to take over and retain the keeper head, and means to swing said latch element in a lateral direction so as to release the keeper.

45 9. A structure as defined in claim 8, in which said latching element is a lever pivoted adjacent the rear end of said wall and having adjacent the free end a lug movable in a slot in said wall.

10. In a latch for hoods having a fixed hood body and 50 a rearwardly hinged lid one of which parts carries at the forward end a postlike keeper uprightly disposed and having a distal head: a guide member for the keeper in fixed relationship to the other of said parts having rearwardly directed parallel guide walls and a connecting wall 55 extending toward the keeper, a latch movably mounted with relation to the walls for engagement with the keeper in a normal closed position, a safety catch carried by one of the side walls for engaging the keeper and holding it in a partially released or safety position.

60 11. In a latch for hoods having a fixed hood body and a rearwardly hinged lid one of which parts carries at the forward end a postlike keeper uprightly disposed and having a distal head: a latch member carried by the other of said parts having a horizontally swingable primary 65 latch lever co-acting with the keeper head, said latch member being further provided with an uprightly disposed guiding member having parallel walls co-acting with the keeper head for guidance of the lid in closing, one of said walls having a slot, and a laterally swingable spring-biased safety catch lever having a lug extending through said slot to engage the keeper head.

70 12. In a latch for hoods having a fixed hood body and a rearwardly hinged lid one of which parts carries at the forward end a postlike keeper uprightly disposed and 75 having a distal head: a latch member carried by the other

of said parts having parallel upright walls engageable with the keeper head for guidance of the lid in closing, said latch member also having primary and secondary latch levers co-operating with the keeper head and movable in substantially parallel horizontal planes, the secondary lever being operable by the primary lever after the primary lever has released the keeper head.

13. A structure as defined in claim 12, in which said guide member is mounted on the hood body with said parallel walls extending in a rearward direction and in which the part of the guide member disposed toward the front of the hood is equipped with a spring-pressed lid-lifting stem.

14. In a latch for hoods having a fixed hood body and a rearwardly hinged lid one of which parts carries at the forward end a postlike keeper uprightly disposed and having a distal head: a latch member carried by the other of said parts having opposing parallel upright walls engageable with the keeper head for guidance of the lid in closing, said latch member also having spring-biased primary and secondary latch levers co-operating with the keeper head and movable in parallel planes, and means operable from the front of the hood to move said levers to releasing position.

15. In a hood latch assembly a latch structure and a keeper, one to be mounted on an automobile hood and the other on an automobile closure for said hood, said latch structure comprising a plate, said plate having an aperture adapted to be penetrated by said keeper, means extending from one face of said plate adjacent to the periphery of the aperture to prevent interlocking of the keeper and plate, a pair of spaced, generally parallel walls mounted on the opposite face of said plate and extending therefrom in axial alignment with said aperture a distance substantially equal to the length of said keeper, said walls being spaced apart a distance substantially equal to the largest diameter of said keeper whereby said walls are effective to serve as a guide for said keeper in the course of its travel toward said aperture, said spaced walls being joined by a third wall of equal extension from said plate with said spaced walls and a latch movably mounted with relation to said plate for engagement with said keeper.

16. In a hood latch assembly a latch structure and a keeper, one to be mounted on an automobile hood and the other on an automobile closure for said hood, said latch structure comprising a plate, said plate having an aperture adapted to be penetrated by said keeper, projection structure substantially surrounding said aperture and extending from one face of said plate, a pair of spaced, generally parallel walls mounted on the opposite face of said plate and extending therefrom in axial alignment with said projection structure and said aperture a distance substantially equal to the length of said keeper, said walls being spaced apart a distance substantially equal to the

largest diameter of said keeper whereby said walls are effective to serve as a guide for said keeper in the course of its travel toward said aperture, said spaced walls being joined by a third wall of equal extension from said plate with said spaced walls and a latch movably mounted with relation to said plate for engagement with said keeper.

17. In a hood latch assembly a latch structure and a keeper, one to be mounted on an automobile hood and the other on an automobile closure for said hood, said latch structure comprising a plate, said plate having an aperture adapted to be penetrated by said keeper, a pair of spaced, generally parallel walls mounted on one face of said plate and extending toward the keeper in axial alignment with said aperture a distance substantially equal to the length of said keeper, said walls being spaced apart a distance substantially equal to the largest diameter of said keeper whereby said walls are effective to serve as a guide for said keeper in the course of its travel toward said aperture, said spaced walls being joined by a third wall of equal extension from said plate with said spaced walls and a latch movably mounted with relation to said plate for engagement with said keeper.

18. In a hood latch assembly, a latch structure and a keeper, one to be mounted on an automobile hood and the other on an automobile closure for the hood, the latch structure comprising a pair of spaced generally parallel walls substantially equal to the length of the keeper and extending toward the keeper, said walls being spaced apart a distance substantially equal to the largest diameter of the keeper whereby the walls are effective to serve as a guide for said keeper in the course of the hood closure travel toward its closed position, said spaced walls being joined by a third wall, a latch movably mounted with relation to the walls for engaging the keeper in a normal closed position, and a safety catch carried by one of the side walls for engaging the keeper and holding it in a partially released or safety position.

UNITED STATES PATENT OFFICE
CERTIFICATE OF CORRECTION

Patent No. 2,852,293

September 16, 1958

Arthur Claud-Mantle

It is hereby certified that error appears in the printed specification of the above numbered patent requiring correction and that the said Letters Patent should read as corrected below.

Column 1, line 31, for "Another" read -- A further --; column 3, line 5, for "wtih" read -- with ---; column 5, line 68, for "embraces" read -- embrace ---; column 6, line 4, for "located in the vertical direction." read -- into a position in which the keeper head is accurately located in the vertical direction. --; column 9, lines 59 and 60, for "latch which lever is swingable in a plane substantially positions." read -- latch lever pivotally so as to move them to their releasing positions. --.

Signed and sealed this 6th day of January 1959.
